UNITED STATES PATENT OFFICE.

CLARANCE W. THOMPSON, OF WILMINGTON, DELAWARE.

VEHICLE-SPRING.

63,541.

Specification of Letters Patent. Patented Dec. 28, 1920.

Application filed March 24, 1920. Serial No. 368,309.

To all whom it may concern:

Be it known that I, CLARANCE W. THOMPSON, a citizen of the United States, residing at Wilmington, in the county of New Castle 5 and State of Delaware, have invented certain new and useful Improvements in Vehicle-Springs, of which the following is a specification.

The invention relates to devices for supporting a body or equivalent part resiliently on the running-gear of a vehicle, and particularly to those that include counteracting springs that sustain the thrusts, shocks, and stresses resulting from irregularities in 15 a roadway and cushion the rebound that occurs after absorption thereof.

It is an object of the invention to provide a device of that kind that will be sensitive to and readily absorptive of thrusts, 20 shocks, and stresses, and at the same time will afford sufficient support for a load under all conditions of service.

The invention also includes means whereby increased resistance of spring action is 25 afforded between a running-gear and a body or its equivalent when comparatively heavy or violent thrusts, shocks, or stresses are sustained.

Means are provided for adjusting the tension of both the load-sustaining and rebound springs.

When read in connection with the description herein, the details of construction and arrangement of parts contemplated by the 35 invention will be apparent from the accompanying drawings, forming part hereof, wherein an embodiment of the invention is disclosed, for purposes of illustration.

While the disclosures herein are considered to exemplify what now is considered to be a preferable embodiment of the invention, it is to be understood that it is not the intention to be limited necessarily thereto in interpretation of the claims, as modifications and adaptations within the limits of 45 the claims can be made without departing from the characteristics of the invention.

Like reference-characters refer to corresponding parts in the views of the drawings, of which—

Figure 1 is a longitudinal sectional view;

Fig. 2 is a transverse sectional view on the line 2—2, Fig. 1;

Fig. 3 is a transverse sectional view on the line 3—3, Fig. 1;

Fig. 4 is an elevation of the device and the members by which it is mounted in association with a vehicle; and

Fig. 5 is an outline elevation of a motor-vehicle equipped with the device.

Having more particular reference to the drawings, 9 designates an elongated housing or casing, preferably of cylindrical form and of uniform cross-sectional dimension throughout its length.

The housing is closed at one end by a disk 10 screwed thereto. The disk constitutes an abutment for a spring yet to be described. It has an enlarged head 11 shaped to receive a wrench or other turning-tool, and it is provided with a passage, closed by a plug 12, for injecting lubricant into the interior of the housing.

An elongated guide 13, preferably in the form of a round rod, is mounted by being 75 screwed into the disk 10, there being a lock-nut 14 on the outer end of the guide to hold it firmly in place. The guide extends from the disk centrally of and to the other end of the housing.

A head 15 is mounted in the end of the housing opposite to the disk 10 by having an exteriorly-threaded annular flange 16 thereof screwed into the housing, and the head has an enlarged outer portion 17 85 shaped to receive a wrench or other turning-tool. The flange affords an abutment or seat for a spring hereinafter described.

The head has a central opening into which there is screwed and from which extends 90 inwardly an exteriorly-threaded sleeve 18. The sleeve has inside of it one or more sets of ball or other suitable anti-friction bearings 19, it is shaped at its outer end 20 to receive a wrench or other turning-tool, and in that end it has a packing-space 21 closed 95 by a gland 22. The sleeve is adjustable longitudinally of the housing by turning in its threads.

A hollow load-sustaining member 23, preferably in the form of a round rod, extends into the housing through the sleeve 18 and over the guide 13. The member 23 is of uniform transverse dimension from its exterior to a place normally in the sleeve, 105 where it has an annular abutment or shoul-

der 24, and it extends therefrom in reduced size to its inner end.

The smaller portion of the member 23 adjacent to the abutment 24 is exteriorly threaded and has screwed thereon a sleeve 25. A laterally-extending annular flange or shoulder 26 is slidable on the smaller portion of the member 23, it normally is in abutment with an end of the sleeve 25, and its position on that member and its limit of movement in one direction may be altered by turning the sleeve in its threads. The shoulder may be of a size to have sliding engagement with the wall of the housing 9, or it may be of a size to permit the interposition of balls 27 or other suitable anti-friction elements between its periphery and the wall of the housing.

During movement in the housing, the member 23 is guided by the sleeve 18 (or its anti-friction bearings 19), by the shoulder 26 bearing directly or through anti-friction bearings against the wall of the housing, and by the guide 13, which latter fits snugly inside of the member 23.

The inner end portion of the member 23 carries a nut 28, which operates to retain on that member a slidable collar 29 by engagement with an interior annular shoulder 30 thereof. The limit of sliding movement of the collar in one direction may be altered by turning the nut. The major portion of the collar normally extends over and beyond the nut and the end of the member 23, and it has on its free end portion an exterior annular abutment 31.

The parts hereinbefore described are arranged to have load-sustaining and rebound springs associated therewith.

40 One of those elements is a comparatively large and strong load-sustaining compression-resisting coil-spring 32 interposed between the disk 10 and the shoulder 26 on the member 23.

45 An auxiliary or safety compression-resisting coil-spring 33, inside of the spring 32, is interposed between the shoulder 26 and the abutment 31 of the collar 29.

A compression-resisting rebound-absorbing coil-spring 34 is interposed between the shoulder 26 and the flange 16.

The device may be interposed between a running-gear and a body or its equivalent of a vehicle in any suitable manner. For example, the housing 9 may be connected with a part of the running-gear or of the body by a bracket or the like A extending laterally therefrom. The member 23 may have at its outer end a ball B in a socket 60 of a member C arranged to be secured to the body or running-gear of the vehicle. A form of installation in a motor-vehicle is disclosed by Fig. 5, wherein the housing is connected with a member of the running-

gear and the member 23 with the body, one 65 of the devices being used on each side at the front and two on each side at the rear. If desired, however, the devices may be reversed, and the housing connected with the body and the member 23 with the running-gear.

The parts are shown in the positions they occupy when no load is imposed on the device. Then the relative tension of the springs is such that the slidable shoulder 26 is 75 against the end of the sleeve 18 under the influence of the expanding property of the main load-sustaining spring 32, and the expansive action of the auxiliary spring 33 keeps the collar 29 against the nut 28 and 80 extended beyond the inner end of the member 23.

The position of the shoulder 26 in the housing in the absence of load is determined by the extent to which the sleeve 18 projects 85 into the housing. The amount of this projection may be altered by turning the sleeve in its threads and thereby changing the relative tension of the three springs. The tension of the auxiliary spring 33 may be altered by turning the nut 28. The extent to which the member 23 extends into the housing in the absence of load may be altered by turning the sleeve 25 and thus changing the at-rest position of the shoulder 26 on that 95 member, which action also will modify the tension of the auxiliary spring.

When, under the action of load, thrusts, shocks, or stresses, the member 23 is moved inwardly of the housing, the shoulder 26, which is carried with the member by the sleeve 25, operates to compress the main spring 32. Ordinarily, the auxiliary spring 33 does not resist such action, as the shoulder 26 and the abutment 31 at first move without relative change of positions. If, however, after initial compression, the main spring 32 does not overcome the action against it before the free end of the collar 29 comes into contact with the end disk 10, action 100 against the auxiliary spring will occur after movement of the collar is stopped by that contact and while the member 23 is moving in the collar, and the auxiliary spring will offer resistance, in addition to that of the 110 main spring, to further movement of the shoulder 26 and the member on which it is mounted.

The auxiliary spring is sufficiently strong to stop relative movement of the parts 120 gradually before the inner end of the member 23 reaches the disk 10, and thus sudden stoppage of such movement and damage that might result therefrom are avoided.

On relief of the device from the action that has caused compression of the main spring, that spring will expand and move the shoulder 26 and the member 23 toward

the end of the housing from which it projects. During compression of the main spring, the rebound-spring 34 has expanded and followed the shoulder 26, and it operates to retard movement of the shoulder and to absorb the expanding rebound action of the main spring. If the rebound effort of the member 23 is not taken up by the time the shoulder 26 is stopped by contact with the end of the sleeve 18, then the auxiliary spring 33 will be compressed during further outward movement of the member and movement of the collar 30 toward that shoulder, and the rebound movement of the member will be brought gradually to an end by that spring.

The arrangement of the parts of the device is such that, while the main spring 32 is sufficiently strong to sustain loads, thrusts, stresses, and shocks ordinarily imposed thereon, the auxiliary spring 32 makes it unnecessary to give to the main spring the ability to resist by itself all of the most violent action to which it sometimes may be subjected in service. Thus the main spring may be made more sensitive to action against it and the device may afford greater comfort and ease than otherwise would be the case.

If the auxiliary spring has been compressed, its expansive action thereafter ceases as soon as the collar 30 during the rebound action again has come into contact with the nut 28, and the parts are relieved from action of that spring in the rebound direction before the shoulder 26 reaches the limit of its movement against the sleeve 18. Thus the rebound effort to be absorbed by the spring 34 and subsequently by the auxiliary spring 33 is less than if the expansive action of the auxiliary spring was for a longer period.

Having thus described my invention, what I claim as new, and desire to secure by Letters Patent, is—

45 1. A vehicle-spring device comprising a housing, a load-sustaining member movable in said housing, a main spring arranged to resist movement of said member under the influence of load, and an auxiliary spring arranged to resist further such movement of said member after initial action against said main spring and to resist movement of said member in the opposite direction.

2. A vehicle-spring device comprising a housing, a load-sustaining member movable in said housing, a shoulder slideable on said member, another shoulder arranged to slide on said member on contact with a fixed part, a main spring arranged to resist movement of said member in one direction, and a compression-resisting spring between said shoulders.

3. A vehicle-spring device comprising a housing having oppositely-disposed fixed

abutments therein, a load-sustaining member movable in said housing, a shoulder slideable on said member, a collar arranged to slide on said member on contact with a fixed part, a main compression-resisting spring between one of said fixed abutments and said shoulder, a rebound-resisting spring between said shoulder and said other fixed abutment, and an auxiliary compression-resisting spring between said shoulder and said collar.

4. A vehicle-spring device comprising a housing, a longitudinally-adjustable sleeve in said housing, a load-sustaining member extending into said housing and slideable in said sleeve, a shoulder slideable on said member contactible with said sleeve whereby its movement in one direction is limited, means whereby said shoulder is moved with said member in the opposite direction, and a spring resisting movement of said shoulder in the latter direction.

5. A vehicle-spring device comprising a housing, a longitudinally-adjustable sleeve in said housing a load-sustaining member slideable in said sleeve, a sleeve longitudinally adjustable on said member, a shoulder slideable on said member contactible on one side with said sleeves whereby its movement in one direction is limited, and a spring arranged to resist movement of said shoulder in the opposite direction.

6. A vehicle-spring device comprising a housing, a longitudinally-adjustable sleeve in said housing, a load-sustaining member slideable in said sleeve, a longitudinally-adjustable sleeve on said member, a shoulder contactible on one side with said sleeves whereby its movement in one direction is limited, a collar slideable on said member and adjustable means limiting its sliding movement in one direction, an auxiliary spring between said shoulder and collar, a main spring arranged to resist movement of said shoulder in one direction, and a rebound spring arranged to resist its movement in the other direction.

7. A vehicle-spring device comprising a housing, a load-sustaining member slideable in said housing, a shoulder slideable on said member, means whereby said shoulder is moved with said member under the influence of load, means whereby movement of said shoulder with said member in the opposite direction is limited, a main spring resisting movement of said shoulder under the influence of load, a collar slideable on said member, means whereby movement of said collar is stopped after initial action against said main spring, and an auxiliary compression-resisting spring between said shoulder and collar.

8. A vehicle-spring device comprising a housing, a load-sustaining member slideable in said housing, a shoulder slideable on said

member, means whereby said shoulder is moved with said member under the influence of load, means whereby movement of said shoulder with said member in the opposite direction is limited, a spring resisting movement of said shoulder in the latter direction, a main spring resisting movement of said shoulder under the influence of load, a

collar slidable on said member, means whereby movement of said collar is stopped after 10 initial action against said main spring, and an auxiliary compression-resisting spring between said shoulder and collar.

In witness whereof, I affix my signature.

CLARANCE W. THOMPSON.
